(57) **CLAIM**

The ornamental design for a set of booties for dogs as shown and described.

DESCRIPTION

FIG. 1 is a front perspective view of the front boot of a set of booties for dogs, with a hook and loop surface fastener strap fastened, showing my new design;

FIG. 2 is a right side view thereof;

FIG. 3 is a left side view thereof;

FIG. 4 is a front view thereof;

FIG. 5 is a back view thereof;

FIG. 6 is a top view thereof;

FIG. 7 is a bottom view thereof;

FIG. 8 is a back view of the front boot of the set of booties for dogs shown in FIG. 1, shown in a second configuration with the hook and loop surface fastener strap unfastened;

FIG. 9 is a front perspective view of the rear boot of the set of booties for dogs with the hook and loop surface fastener strap fastened, showing my new design;

FIG. 10 is a right side view thereof;

FIG. 11 is a left side view thereof;

FIG. 12 is a front view thereof;

FIG. 13 is a back view thereof;

FIG. 14 is a top view thereof;

FIG. 15 is a bottom view thereof; and,

FIG. 16 is a back view of the rear boot of the set of booties for dogs shown in FIG. 1, shown in a second configuration with the hook and loop surface fastener strap unfastened.

The broken lines in the drawings illustrate portions of the set of booties for dogs that form no part of the claimed design.

1 Claim, 16 Drawing Sheets
